TYPOGRAPHICAL COMPOSING MACHINE

Hermann Brandenburg, Berlin-Tempelhof, Germany, assignor to Mergenthaler Linotype Company, Brooklyn, N. Y., a company of New York

Application November 17, 1939, Serial No. 304,907
In Germany November 4, 1938

8 Claims. (Cl. 199—44)

This invention relates to typographical composing machines wherein matrices stored in a magazine are released therefrom and composed in a line. In such machines, the matrix magazine is provided with a plurality of separate channels to accommodate the different matrix characters comprised in a complete font and the length of the magazine is such that about 20 matrices can be stored one behind the other in each channel.

In order to have a sufficient number of the most frequently used matrix characters available during composition it is customary to provide two channels for each of the two lower-case matrix characters "e" and "n" which channels are automatically used in alternation. The storage of these most frequently used matrices also necessitates making the magazine of a sufficient length to accommodate 20 matrices one behind the other in a channel, although the remaining matrix characters of the font are less frequently used and a smaller number thereof would suffice so that some of the storage space available in the magazine is superfluous.

The object of the invention is to provide a magazine of such a form that the magazine channels are fully utilised so enabling the length and weight of the magazine to be reduced and the operation of magazine changing thereby facilitated. This object is achieved by decreasing the length of the magazine and increasing the number of magazine channels for the most frequently used matrix characters to an extent which is sufficient to accommodate the normal quantity of these matrices. The matrix characters are preferably arranged in the magazine in an order which corresponds with their frequency of use in composition there being just sufficient matrices in each channel for ordinary use. The top edges of the matrices at the upper end of the magazine are thus located along an inclined line. The magazine according to the invention is divided along this line into a stationary upper section and an interchangeable lower section.

In the drawing, a plan of one constructional form of the invention is illustrated in diagrammatical form.

The customary form of magazine illustrated by a broken line *a* has at its lower end a width *b* and at its upper end a width *b*¹, which are such as to accommodate the number of magazine channels, usually 91, which are required for storing the different matrices in a font. As is customary, the magazine channels converge from the upper end of the magazine towards the lower

delivery end thereof. The length *c* of the magazine is such that about 20 matrices may be stored one behind the other in each channel.

According to the invention, the said length *c* of the magazine is reduced to the length *d*, which is approximately $\frac{2}{3}$ of the length *c*. In order to accommodate in a magazine of such reduced length the required number of the most frequently used lower-case characters "e" and "n", three channels instead of two are, according to the invention, filled with lower-case "e" matrices and three channels instead of two are filled with lower-case "n" matrices. The channels are operated automatically in succession in a manner similar to the alternate operation of two channels. If, therefore, the original number of these frequently used characters is to be retained, it is necessary to increase the width of the magazine to an extent corresponding to the width of two magazine channels as shown in the drawing at *e*. The increase in the amount of material required for this slight increase in width is however not comparable to the amount of metal and weight saved by the shortening of the magazine. If, therefore, two channels of lower-case "e" and "n" respectively each with 20 matrices were previously provided, three such channels each with 13 matrices are provided according to the invention so that the total number of these matrices remains substantially the same as previously used.

Apart from the lower-case "e" and "n" matrices, there need not be more than from 10 to 12 of the most frequently used matrices and from 3 to 4 of the lesser used matrices in each channel. Thus the shorter magazine according to the invention need not be filled with matrices to its full capacity, and consequently it is possible to make a further saving in the weight of the magazine proper and in the amount of material required. To this end the matrices are arranged in the magazine in an order which corresponds to their frequency of use in composition, that is to say, the most frequently used matrices are accommodated at one side, say the left-hand side of the magazine, and the lesser used matrices are accommodated at the other side, say the right-hand side of the magazine. When the magazine is filled with a complete font of matrices, there being just sufficient matrices in each channel for ordinary use as above described, the top edges of the matrices at the upper end of the magazine are located along an inclined line extending downwardly from left to right. According to the invention, the magazine is divided along the said line so as to form a lower maga-

zine section *f* and an upper magazine section *g*. The magazine section *g* does not contain any matrices, but merely forms a lead-in from the distributor to the lower magazine section *f* in which the matrices are stored. When effecting a magazine change, the section *f* only need be removed whereas the section *g* is always in use and can be permanently mounted on the machine. If the machine is equipped with a plurality of 10 magazines, that is to say a plurality of magazine sections *f* known means may be used for shifting such sections relatively to the stationary section *g* but, if preferred, a separate section *g* permanently located within the machine may be provided for each interchangeable section *f*, and the whole composite magazine shifted when changing from one magazine to another.

In the case of magazines which contain small quantities of matrices having display characters, 20 it is customary for the magazine to be divided in a transverse direction and for the lower part thereof to be made removable when effecting a magazine change. The present invention, however differs from this known arrangement in that 25 the magazine is divided along an inclined line thus providing a lower magazine section which is specially adapted to the composition of a regular font of matrices.

It has been found quite satisfactory in practice 30 to decrease the magazine length to an extent sufficient for storing from 12 to 13 of the most used matrix characters in a magazine channel. The invention, however, is not restricted to a maximum magazine length based on this number of 35 matrices but includes magazines having a length designed to accommodate in the respective channels other numbers of matrices less than the normal number.

It will usually be found adequate if the magazine 40 channels for the lower-case "e" and "n" characters are respectively triplicated as above described. If necessary, however, additional magazine channels may be provided for the storage of frequently used characters, but there 45 will still be a saving of materials and weight notwithstanding the increase in width of the magazine.

An increase in the width of the magazine is not essential for the purposes of the present invention, as such increase can be avoided if the 50 lesser used characters, such as punctuation marks, are eliminated, and hand composed matrices are substituted therefor, so that the channels which would have been occupied by these lesser used 55 characters may be used for storing the lower case "e" and "n" characters or any other frequently used characters.

Having described my invention, I declare that 60 what I claim and desire to secure by Letters Patent is:

1. A magazine for the storage of a font of typographical matrices, of less than standard length, and greater than standard width and having a plurality of channels in each of which 65 matrices are stored one above another, at least three adjacent channels being adapted to accommodate the matrices of one of the most frequently used characters of the font.

2. A magazine for the storage of a font of typographical matrices, of less than standard length and greater than standard width, comprising an upper entrance section and a lower storage section and having a plurality of channels in each of which 70 matrices are stored one above another, at least three adjacent channels being adapted

to accommodate the matrices of one of the most frequently used characters of the font.

3. A magazine for the storage of a font of typographical matrices, of less than standard length and greater than standard width, comprising an upper entrance section and a lower storage section the said sections mutually abutting in a plane inclined transversely, of the magazine, and having a plurality of channels in each of which 5 matrices are stored one above another, at least 10 three adjacent channels being adapted to accommodate the matrices of one of the most frequently used characters of the font.

4. For the storage of a font of typographical matrices consisting of numbers of matrices of individual characters varying in accordance with the frequency of use of the respective characters, a magazine of less than standard length and greater than standard width comprising an upper entrance section and a lower storage section 15 having a plurality of channels in which matrices are stored in an order which corresponds with their frequency of use, said upper and lower sections 20 mutually abutting in a plane inclined transversely of the magazine in accordance with the order of the decreasing number of matrices 25 in the respective channels.

5. For the storage of a font of typographical matrices consisting of numbers of matrices of individual characters varying in accordance with the frequency of use of the respective characters, a magazine of less than standard length and greater than standard width comprising an upper entrance section and a lower storage section having a plurality of channels in which matrices are 30 stored in an order which corresponds with their frequency of use, at least three adjacent channels being adapted to accommodate the matrices of one of the most frequently used characters, said upper and lower sections 35 mutually abutting in a plane inclined transversely of the magazine in accordance with the order of the decreasing number of matrices in the respective channels.

6. For the storage of a font of typographical matrices consisting of numbers of matrices of individual characters varying in accordance with the frequency of use of the respective characters, a magazine of less than standard length and greater than standard width comprising a fixed upper entrance section and an interchangeable lower storage section having a plurality of channels in which matrices are stored in an order which corresponds with their frequency of use, said upper and lower sections 45 mutually abutting in a plane inclined transversely of the magazine 50 in accordance with the order of the decreasing number of matrices 55 in the respective channels.

7. A typographical matrix magazine comprising an upper entrance section and a lower storage section the said sections mutually abutting in a 60 plane inclined transversely of the magazine.

8. For the storage of a font of typographical matrices consisting of numbers of matrices of individual characters varying in accordance with the frequency of use of the respective characters, a magazine of less than standard length and having a plurality of channels in which matrices are stored in an order which corresponds with their frequency of use, said magazine terminating at 65 its upper end in a plane inclined transversely of the magazine in accordance with the order of the decreasing number of matrices in the respective channels.
